UNITED STATES PATENT OFFICE.

THOMAS J. HAYES, OF ROSLINDALE, MASSACHUSETTS, ASSIGNOR TO ARBETTER FELLING MACHINE COMPANY, OF BOSTON, MASSACHUSETTS, A CORPORATION OF MAINE.

FEEDING MECHANISM FOR SEWING MACHINES.

1,410,753.

Specification of Letters Patent. Patented Mar. 28, 1922.

Application filed August 1, 1917. Serial No. 183,963.

To all whom it may concern:

Be it known that I, THOMAS J. HAYES, a citizen of the United States, and resident of Roslindale, county of Suffolk, State of Massachusetts, have invented an Improvement in Feeding Mechanisms for Sewing Machines, of which the following description, in connection with the accompanying drawing, is a specification, like characters on the 10 drawing representing like parts.

This invention relates to improvements in feeding mechanism for sewing machines and the object thereof is to provide means for stretching the work slightly at the stitching point so that when the stitches are set by the take-up mechanism all pulling in or puckering of the goods will be avoided.

In the usual operation of sewing machines of any type, and particularly blind stitch 20 sewing machines in which a bender is employed to present the work to the stitch forming mechanism the portions of the work encompassed by the needle thread are likely to be condensed by the action of the take-up 25 so as to produce slight puckers or checks in the material along the line of stitching. The present invention has for its object the production of feeding mechanism adapted for general use but particularly adapted for use 30 in connection with blind stitch sewing machines which will remedy this defect.

This is accomplished by providing a main feed dog having a work engaging surface operable to advance the work, with a supplemental instrumentality or supplemental instrumentalities operable to stretch the work in the direction of the line of feed at the stitching point, preferably such instrumentalities being located both fore and aft 40 of the stitching point.

Other objects and features of the invention will more fully appear from the following description and the accompanying drawings and will be pointed out in the annexed 45 claims.

The drawings illustrate the invention as applied to a blind stitch sewing machine for felling of the general "Arbette" type and more particularly of the type illustrated in my 50 prior applications No. 108,279, filed July 5, 1916, and No. 140,522, filed January 4, 1917, the latter of which discloses a particular form of feeding mechanism to which the present invention is applied.

In the drawings;

Fig. 1 is a side elevation of a blind stitch sewing machine of the "Arbette type," a portion of the bed plate and standard being shown in section,

Fig. 2 is an enlarged detail view of the work support, feed dog, and means for actuating the same showing my invention applied thereto,

Fig. 3 is a detail elevation of the main feed dog and supplemental feed dogs pivot- 65 ally and yieldably supported thereon.

Fig. 4 is a detail plan view of the same,

Fig. 5 is an end view of the feed dogs illustrated in Fig. 3,

Fig. 6 is a detail side elevation of the supplemental feed dogs removed from the main feed dog but assembled in working position,

Fig. 7 is a plan view of the same, and,

Fig. 8 is an end view thereof showing the position of set screws for retaining the adjusting screws which regulate the yieldable supports for the supplemental feed dog.

The sewing machine illustrated herein comprises a bed plate 1 provided with an upwardly projecting boss 2 forming a base 80 for a standard 3 which carries the usual overhanging arm 4 terminating in a head 5 which supports a curved oscillating needle and complementary stitch forming mechanism. The main shaft 6 is journaled in 85 suitable bearings in the arm and standard and is provided with the usual driving pulley 7. The shaft 6 is provided at its opposite end with suitable means for actuating the needle and complementary stitch forming 90 mechanism, the needle mechanism herein disclosed comprising a curved oscillating needle carried by a needle bar 8 which is oscillated in substantially the direction of the line of feed and is provided with means (not 95 shown) for shogging the same laterally to produce two parallel lines of stitching.

The complementary stitch forming mechanism desirably is of the rotary hook or looper type and is carried by a hook bracket 100 10 depending from the head of the machine, said hook bracket also rigidly supporting the usual presser foot 11 as in the "Arbette" type of machines.

It will however, be understood that any 105 form of needle mechanism and complementary stitch forming mechanism may be employed in connection with my invention,

whether said stitch forming mechanism is of a through and through type or of the blind stitching type such as that illustrated in the accompanying drawings.

5 Any suitable work presenting mechanism may be employed and equipped with the invention constituting the subject matter of the present application. As illustrated herein the work supporting member is in the 10 form of a rectangular block 12 which extends through the bed plate 1 and desirably is provided with a removable cap 13 slotted to accommodate the rows of teeth of the feed dogs. The work supporting member 12 is 15 provided at its ends with extensions which terminate in bosses 14, 15 which form journals for the ends of rock shafts 16, 17 which serve to operate the feed dogs as will hereinafter more fully appear.

20 The work supporting member is also provided with projecting members 18, 19 and 20 and which extend toward the end of the machine, the members 18 and 20 having secured thereto downwardly depending arcuate guides 21 and 22 which are provided with longitudinal slots, (see Fig. 1). The guides 21 and 22 embrace and are slidably mounted upon the outer walls of a bracket 23, the base 24 of which is secured to the 25 under surface of the bed plate. This bracket is provided at its lower end with a transverse web 25 having a central screw 26 which engages and supports the lower end of a helical spring 27, the upper end of which 30 engages the extension 19 of the work support and normally maintains said work support in engagement with the presser foot 11. By the adjustment of the screw 26 the pressure of the work support against the presser 35 foot may be regulated in the usual manner.

The feeding mechanism in the preferred embodiment of the invention disclosed herein is carried upon the shafts 16 and 17 and comprises a feed bar 28 pivotally connected 40 at one end to an arm 29 of the rock shaft 16, the other end of said feed bar being bifurcated to form a way 30 in which a block or cross head 31 is reciprocably mounted, said block 31 being pivotally mounted upon a stud 32 projecting from an arm 33 upon the shaft 17.

Suitable means are provided for oscillating the rock shafts 16 and 17, the oscillation of the rock shaft 16 operating to advance and retract the feed bar and the feed dog which is carried thereupon, while the oscillation of the rock shaft 17 serves to raise and lower the feed dog into and out of engagement with the work in a well known manner.

60 The feed dog 34 preferably is of substantially rectangular form and is provided with a central throat 35 to receive the bender, said throat being located directly beneath the stitching point of the stitch forming mecha-

nism. The work engaging surfaces 36 and 37 of the main feed dog 34 extend along the sides of the central throat opening in the direction of the line of feed. The feed dog 34 has adjacent its end downward extensions 70 or legs 38, 39 which rest upon the feed bar 28 and are secured to it by screws 40, 41.

The construction thus described is substantially that disclosed in my companion application No. 141,522 aforesaid and in this 75 mechanism as that disclosed in said application the work support and feed dog are alternately raised to press the work against the presser foot, the work support sustaining the work against the presser foot during the 80 stitch forming operation and the feeding mechanism serving to advance the work in the usual manner.

In the operation of sewing machines of all 85 types and particularly the blind stitching type in which a bender presents the work to the stitch forming mechanism there is a tendency to condense or pucker the work inclosed by the needle thread when the stitch is set by the take-up. This produces lines 90 of "checks" extending laterally from the line of stitching, which are unsightly and this pucker of the goods when excessive also interferes with the proper formation of the garment. 95

The present invention is designed for the purpose of stretching the work at the stitching point sufficiently to prevent the condensing or pucker of the goods in the line of stitching, and the invention contemplates 100 broadly the provision of means for accomplishing this function as applied to any form of sewing machine wherein it may be found desirable.

A preferred embodiment of the invention 105 is illustrated herein as applied to a blind stitch sewing machine as above described. In this construction the main feed dog 34 is channelled longitudinally to provide a recess to receive the supplemental work engaging instrumentalities which are adapted to stretch the work at the stitching point. These instrumentalities as illustrated herein comprise supplemental feed dogs which are located fore and aft of the throat 35 and in 110 the vertical plane of the line of feed.

The supplemental feed dogs 42, 43 are conveniently made of substantially rectangular plates, the dog 42 having a serrated surface 44, the teeth of which extend in the 115 direction of feed, while the feed dog 43 has a serrated work engaging surface in which the teeth 45 extend in the opposite direction or against the direction of feed. The feed dogs 42 and 43 are provided respectively 120 with laterally offset arms 46 and 47 which extend along the throat 35 and are pivoted respectively on pins or shafts 49 and 50 which are journaled in the walls of the main feed dog 34. The supplemental feed 125

dogs 42 and 43 are provided respectively with recesses 51, 52 through which the shafts 50 and 49 extend, the upper and lower walls of the recess serving to limit the vertical 5 movement of said supplemental feed dogs.

The supplemental feed dogs are normally sustained with their work engaging surfaces 44, 45 above the work engaging surfaces 36, 37 of the main feed dog by helical 10 springs 53, 54, the upper ends of which engage the under sides of the arms 47 and 46 respectively. The lower ends of the springs 53 and 54 are seated upon adjusting screws 55 and 56 which extend upwardly through 15 suitable screw threaded apertures in the lugs 38 and 39 of the feed dog.

By adjusting the screws 55 and 56, therefore the springs 53 and 54 may be given any desired degree of compression to cause a 20 more or less firm engagement of the supplemental feed dogs 44 and 45 with the work or to adjust the height to which the supplemental feed dogs are normally positioned above the work engaging surface of the 25 work support. The adjusting screws 55 and 56 may be locked in adjusted position by set screws 57 and 58 extending laterally through the lugs 38, 39 of the feed dog and abutting against the adjusting screws 55 30 and 56.

In the operation of the machine the spring 27 normally forces the work support toward the presser foot to clamp the work therebetween during the stitch forming operation. The oscillation of the rock shafts 16 and 17 cause the feed dog to rise into engagement with the work and upon further upward movement to force the work support downwardly against the helical spring 40 27 so as to release the work. Thereupon the feed dog advances to cause the feeding movement. At the end of the feeding movement the feed dog is depressed and the work support again engages and clamps the work for 45 the next step.

By reason of the fact that the work engaging surfaces of the supplemental feed dogs are normally positioned above the work engaging surface of the main feed dog they 50 first engage the work upon the upward movement of the feed dogs and by reason of their pivotal connection are forced apart so as to stretch the work in the line of stitching. The main feed dog then also clamps 55 the work against the presser foot and retains the same in that position until the work support rises to clamp the work against the presser foot. The work is thereby retained in a stretched condition at the stitching 60 point while the needle thread is passed through it and the stitch formed and set. When the work is released by the withdrawal of the work support from the presser foot the elasticity of the goods draws it back 65 to its original position and the concatenated

loops of thread embrace the portions of the work in a normal condition so that the stitches are sufficiently loose not to pucker or condense the material embraced by them. By reason of this construction and operation 70 a seam is made which is smooth and without pockers or checks.

While two supplemental feed dogs have been illustrated herein as the preferred embodiment of the invention it will be obvious 75 that a single supplemental feed dog may be utilized and under certain conditions arranged either in front or behind the stitching point. It will also be understood that other work engaging instrumentalities may 80 be employed to perform the function aforesaid within the meaning and scope of my invention. The following claims, therefore are intended to cover any form of supplemental work engaging means operable to 85 stretch the work in the direction of the line of feed at the stitching point.

Having thus described my invention what I claim as new and desire to secure by Letters Patent is:

1. Feeding mechanism for sewing machines comprising a main feed dog having a work engaging surface, means for actuating said dog to advance the work, and supplemental work engaging instrumentalities located fore and aft of the stitching point, 90 means for moving one of said work engaging instrumentalities in the same direction as that of the movement of the main feed dog and also relatively to said main feed dog 95 and means for moving the other of said instrumentalities simultaneously in the opposite direction whereby a portion of the work engaged by said supplemental work engaging members will be stretched at the stitching point.

2. Feeding mechanism for sewing machines comprising a main feed dog having work engaging surfaces, means for actuating said dog to advance the work and supplemental work engaging instrumentalities located fore and aft of the stitching point positioned to engage the same surface of the work as that engaged by the main feed dog and means for moving said supplemental 110 work engaging instrumentalities simultaneously relatively to said main feed dog and in opposite directions to stretch the work in the direction of the line of feed at the stitching point.

3. Feeding mechanism for sewing machines comprising a main feed dog having a central throat located at the stitching point and parallel roughened work engaging surfaces at the side of said central throat, a 125 supplemental feed dog mounted upon said main feed dog intermediate of the work engaging surfaces thereof and normally projecting above said main feed dog, said supplemental feed dog being located at the rear 130

of the central throat and means for moving said supplemental feed dog rearwardly relatively to said main feed dog when forced into engagement with the work and thereby 5 to stretch the work from the stitching point rearwardly.

4. Feeding mechanism for sewing machines comprising a main feed dog having a central throat located at the stitching point 10 and parallel roughened work engaging surfaces at the sides of said central throat, a supplemental feed dog mounted upon said main feed dog intermediate of the work engaging surfaces of said main feed dog and 15 located in advance of said central throat and means for moving said supplemental feed dog relatively to said main feed dog in the opposite direction to that of movement of the main feed dog and acting to retard the 20 feeding of the work thereby stretching it at the stitching point.

5. Feeding mechanism for sewing machines comprising a main feed dog having a central throat at the stitching point and 25 parallel work engaging surfaces upon opposite sides of said central throat, a supplemental feed dog having a work engaging surface normally yieldably supported above the work engaging surface of the main feed 30 dog, means pivotally connecting said supplemental feed dog to said main feed dog operable to cause said supplemental dog to move relatively to the main feed dog when the work engaging surface of said supplemental 35 dog is depressed to the plane of the work engaging surface of the main feed dog.

6. Feeding mechanism for sewing machines comprising a main feed dog having a 40 central throat at the stitching point, and parallel work engaging surfaces upon opposite sides of said central throat, supplemental feed dogs located fore and aft of said central throat having their work engaging 45 surfaces normally yieldably supported above the work engaging surface of the main feed dog and means pivotally connecting said supplemental dogs to said main feed dog to cause said supplemental dogs to advance in 50 opposite directions when their work engaging surfaces are depressed to the plane of the work engaging surface of the main feed dog.

7. Feeding mechanism comprising a main 55 feed dog having a central throat at the stitching point and a work engaging surface extending in the direction of the line of feed, supplemental feed dogs located fore and aft of said central throat, adjustable means 60 yieldably supporting said supplemental feed dogs with their work engaging surfaces normally above the work engaging surface of the main feed dog and means connecting said supplemental feed dogs to said main feed 65 dogs to cause said supplemental feed

dogs to advance in opposite directions when their work engaging surfaces are depressed to the plane of the work engaging surface of the work support.

8. Feeding mechanism comprising a main 70 feed dog having a central throat at the stitching point and a work engaging surface extending in the direction of the line of feed, supplemental feed dogs located fore and aft of said central throat, helical springs supporting said supplemental feed dogs with their work engaging surfaces normally above the work engaging surface of the main feed dog, screws for adjusting said helical springs and means pivotally connecting said supplemental feed dogs to said main feed dogs to cause said supplemental feed dogs to advance in opposite directions when their work engaging surfaces are depressed to the plane of the work engaging surface of the main 85 feed dog.

9. Feeding mechanism for sewing machines comprising a main feed dog having a central throat at the stitching point and parallel work engaging surfaces upon opposite sides of said central throat, supplemental feed dogs located fore and aft of said 90 throat having arms pivoted respectively at the opposite ends of said main feed dog means yieldably supporting said feed dogs 95 with their work engaging surfaces above the work engaging surface of the main feed dog whereby upon depression of the work engaging surface of the supplemental feed dogs to the plane of the work engaging surface of 100 the main feed dog said supplemental feed dogs will be separated to stretch the work at the stitching point.

10. Feeding mechanism for sewing machines comprising a main feed dog having a 105 central throat at the stitching point and parallel work engaging surfaces upon opposite sides of said central throat, supplemental feed dogs located fore and aft of said 110 throat having arms pivoted respectively at the opposite end of said main feed dog, means yieldably supporting said feed dogs with their work engaging surfaces above the work engaging surface of the main feed dog whereby upon depression of the work engaging surface of the supplemental feed dogs to the plane of the work engaging surface of the main feed dog said supplemental feed dogs 115 will be separated to stretch the work at the stitching point and means for adjusting said 120 yieldable supporting means.

11. In a blind stitch sewing machine comprising a work support, an overhanging arm having a head carrying a presser foot, a curved oscillating needle and complementary 125 stitch forming mechanism, means for actuating said stitch forming mechanism, work presenting mechanism including a bender and means for actuating the same and feeding mechanism comprising a main feed dog 130

- having a central throat to receive said bender, work engaging surfaces extending in the direction of the line of feed located at the sides of said central throat, means for actuating said main feed dog, supplemental work engaging instrumentalities located fore and aft of said central throat and means for actuating said supplemental instrumentalities to stretch the work at the stitching point.

12. In a blind stitch sewing machine comprising a work support, an overhanging arm having a head, a presser foot rigidly secured to said head, a curved oscillating needle and complementary stitch forming mechanism supported by said head and means for actuating said stitch forming mechanism, work presenting mechanism comprising a bender and means for actuating the same, a yieldable work support and feeding mechanism comprising a main feed dog having a central throat opening to receive said bender and work engaging surfaces extending in the direction of the line of feed located at the sides of said central throat, means for actuating said main feed dog, supplemental feed dogs located fore and aft of said main feed dog, means for yieldably supporting said supplemental feed dogs with their work engaging surfaces extending above the plane of the work engaging surfaces of said main feed dog, means connecting said supplemental dogs to said main feed dog operable when said supplemental feed dogs are depressed in their co-operation with the presser foot to cause said supplemental feed dogs to advance in opposite directions to stretch the work at the stitching point.

13. In a blind stitch sewing machine comprising a work support, an overhanging arm having a head, a presser foot rigidly secured to said head, a curved oscillating needle and complementary stitch forming mechanism supported by said head and means for actuating said stitch forming mechanism, work presenting mechanism comprising a bender and means for actuating the same, a yieldable work support, and feeding mechanism comprising a main feed dog having a central throat opening to receive said bender and work engaging surfaces extending in the direction of the line of feed located at the sides of said central throat, means for actuating said main feed dog, supplemental feed dogs located fore and aft of said main feed dog, means for yieldably supporting said supplemental feed dogs with their work engaging surfaces extending above the plane of the work engaging surfaces of said main feed dog, means for adjusting said yieldable sup-

porting means, means connecting said supplemental dogs to said main feed dog operable when said supplemental feed dogs are depressed in their co-operation with the presser foot to cause said supplemental feed dogs to advance in opposite directions to stretch the work at the stitching point.

14. In a blind stitch sewing machine comprising a base, an overhanging arm having a head carrying a presser foot, a curved oscillating needle and complementary stitch forming mechanism and means for actuating said stitch forming mechanism, rock shafts pivotally mounted upon said base and carrying at their free ends a work support and feeding mechanism, means for yieldably forcing said work supporting and feeding mechanism toward said presser foot and means for oscillating said rock shafts to cause said work support and feeding mechanism to co-operate with said presser foot and stitch forming mechanism, said feeding mechanism comprising a main feed dog having a work engaging surface and supplemental work engaging instrumentalities located fore and aft of the stitching point and means for actuating said supplemental work engaging instrumentalities which stretch the work in the direction of the line of feed at the stitching point.

15. In a blind stitch sewing machine comprising a base, an overhanging arm having a head carrying a presser foot, a curved oscillating needle and complementary stitch forming mechanism and means for actuating said stitch forming mechanism, rock shafts pivotally mounted upon said bases and carrying at their free ends a work support and feeding mechanism, means for yieldably forcing said work support and feeding mechanism toward said presser foot and means for oscillating said rock shafts to cause said work support and feeding mechanism to co-operate with said presser foot and stitch forming mechanism, said feeding mechanism comprising a main feed dog having a work engaging surface and supplemental work engaging instrumentalities located fore and aft of the stitching point and means for actuating said supplemental work engaging instrumentalities which stretch the work in the direction of the line of feed at the stitching point, a bender pivotally mounted upon said base and means for actuating said bender to present the work to the stitch forming mechanism.

In testimony whereof, I have signed my name to this specification.

THOMAS J. HAYES.

In testimony whereof, I have signed my name to this specification.

THOMAS J. HAYES.
